United States Patent Office

Des. 214,858
Patented Aug. 5, 1969

214,858

LUGGAGE CASE

Anthony N. D'Elia, Riverdale, and Edward M. Stolarz,
Yorktown Heights, N.Y., assignors to Reliable Luggage
Incorporated, Pittsburgh, Pa., a corporation of
Pennsylvania

Filed Mar. 20, 1968, Ser. No. 11,066

Term of patent 14 years

Int. Cl. D3—01

U.S. Cl. D87—5

FIG. 1

FIG. 2

FIG. 4

FIG. 3

FIG. 5

FIG. 1 is a front perspective view of a luggage case embodying our new design;

FIG. 2 is a side elevational view thereof, the opposite side being identical;

FIG. 3 is a rear elevational view thereof;

FIG. 4 is a top plan view thereof;

FIG. 5 is a bottom plan view thereof.

The surface shading in FIGS. 1, 3, and 4 represents fabric which is continuous on the front and rear panels of the luggage case.

We claim:

The ornamental design for a luggage case, as shown and described.
